W. H. RICHARDS
COLLAPSIBLE FILLING PLUG

Filed Aug. 4, 1922.

FIG. 4.

Inventor
W. H. Richards

By
Robert H. Young
Attorney

UNITED STATES PATENT OFFICE.

WILLIAM H. RICHARDS, OF DAYTON, OHIO.

COLLAPSIBLE FILLING PLUG.

Application filed August 4, 1922. Serial No. 579,735.

To all whom it may concern:

Be it known that I, WILLIAM H. RICHARDS, a citizen of the United States, residing at Dayton, in the county of Montgomery and State of Ohio, have invented certain new and useful Improvements in Collapsible Filling Plugs, of which the following is a specification.

This invention relates to collapsible filling 10 plugs and more particularly to filling plugs for liquid containers although its uses in other connections are apparent.

It is an object of this invention to provide a filling plug, funnel and cover combined 15 which will be efficient and simple of operation and will be capable of being opened or closed in an instant. To these ends means are provided whereby the funnel is pulled out and the cover opened, ready for the filling 20 operation, in one continuous movement. So too, in closing the device one movement only is required.

It is a further object to provide a collapsible funnel means in conjunction with 25 the usual filling plug and so connected thereto that the container may be filled either with or without pulling out, i. e. extending the funnel.

It is a further object to so arrange the 30 collapsible funnel with a filling plug that it may be used for automobile or airplane radiators.

Further objects will be obvious from the 35 claims and from the description of the drawing in which:—

Figure 1 is a vertical section of the invention as attached to the filling plug of an automobile radiator and taken on line I—I of Figure 3.

40 Figure 2 is a similar view in expanded section taken at right angles to the view of Figure 1.

Figure 3 is a top plan view of a preferred embodiment of the invention and

45 Figure 4 is a part of the device in section showing the cover latching means.

Referring to the parts in detail, 2 designates an ordinary radiator filling plug which is provided with a flanged member 4 in the 50 shape of an oval cup and which is also provided with screw threads 6 or other means whereby it may be attached to the radiator, in this case, of an automobile. A circular or oval (not shown) collapsible cup 8 com-

posed of a plurality of telescoping sections, 55 is placed within the cup guard and support 4 and surrounds the filling plug 2 at its upper end, being retained therein by tapered collar 10 which is secured to plug 2 in any suitable manner, such as by screw threads, 60 brazing, warping etc. The collar 10 is also tapered inwardly as shown at 10^a in order to prevent splashing while filling the radiator. As shown, the plug 2 is beaded over the collar 10 as at 12 to secure the collar 65 thereon. The plug 2 is provided with interiorly projecting flanges 14 for a purpose later described. Drain holes 8^a are provided in the support 4.

The cup 8 is provided with a cover 16, 70 hinged to the top section as at 18 and a reinforcing ring of wire or suitable material 20 completely encircles the top section.

The latching means shown in Figure 4 75 comprises a latch member 22 secured to a spring 24 riveted or otherwise secured to the outside section of the cup at 26. The latch 22 is provided with a detent 28 which permits the latch to snap over the cover 16 and the cover is recessed as at 30 to allow 80 the latch to pass therethrough. The cup guard and support 4 may be recessed as at 30^a for a similar purpose.

The cover is provided with a handle 32 85 attached to a spindle 34 attached in turn to cover 16 by flange 36. The spindle 34 has riveted thereto at its lower end a spring clip 38 which upon turning the handle 32 is engaged or disengaged at its ends with flanges 14, aforementioned.

It will be seen that to prepare to fill the container through my device, that it is only necessary to give handle 32 a small rotational movement, lift up on it pulling the telescoping segments of the cup out until they lock and then to release the cover 16 by depressing lever 22, so that it may be swung back to the dotted line position 40 of Figure 1.

100 I claim:

1. A collapsible filling device comprising, a collapsible cup, a combined filling pipe and cup container, a cover for said cup, means whereby said cup may be collapsed and locked or unlocked and extended and means 105 whereby said cover may be subsequently opened upon the extension of said cup.

2. A device of the character described

comprising, a filling pipe adapted to position a telescopic funnel thereon, a funnel of such character thereon, a guard for said funnel exteriorly adjacent said filling pipe 5 and a cover for said funnel.

3. A device of the character described comprising, a filling pipe adapted to position a collapsible funnel thereon, a funnel of such character thereon, a guard for said 10 funnel exteriorly adjacent said filling pipe and integral therewith, a cover for said funnel, means to lock and unlock said funnel to and from said pipe when said funnel is collapsed and means to unlock said cover from 15 said funnel subsequently to unlocking said funnel.

4. In a device of the character described, a filling pipe and cup shaped guard adjacent thereto, a collapsible funnel between said 20 guard and pipe and positioned on a downwardly converging tapered collar attached

to said pipe and locking cover means for said funnel.

5. In combination with a radiator having a filling tube, of a funnel support on the outer side of said tube, a collapsible filling funnel on the outside of said tube having a cover and adapted to rest on said support when collapsed and means for releasably securing said funnel to said tube and support. 25

6. In combination with a radiator having a filling tube, of a funnel support on the outer side of said tube, a collapsible filling funnel on the outside of said tube having a cover and adapted to rest on said support when collapsed, means for releasably securing said funnel to said tube and means whereby said cover may be releasably secured to said funnel. 30 35

In testimony whereof I affix my signature. 40
WILLIAM H. RICHARDS.
